HAIR DEVICE

William Huppert, New York, N. Y., assignor to
Delamere Company, Inc., a corporation of Dela-
ware

Application April 14, 1939, Serial No. 267,763

4 Claims. (Cl. 132—38)

This invention relates to a hair device, and more particularly to a device comprising a flexible form on which the hair may be rolled, a pliable wire extending lengthwise across the form to clasp the ends of the hair thereon, and ribbons for fastening the device to the head.

The principal object of my invention is to provide a flexible hair device of light weight for forming and setting the hair at the back of the head in a roll, either with the hair turned under in the style commonly known as "page-boy bob" or with the hair turned up.

A further object is to provide a device of this character that may be easily applied to the head of the wearer and comfortably worn while the roll is being set.

A further object is to provide a device of this character that permits of free ventilation and circulation of air so that the hair supported on the roll may be quickly dried and set.

The invention is illustrated in the accompanying drawing in which:

Figure 1 is a side elevation, partly broken away, of a hair device embodying the invention;

Fig. 2 is a sectional view of an end thereof, on a slightly larger scale;

Fig. 3 is a cross-sectional view on the line 3—3 of Figure 1;

Fig. 4 is a view similar to Figure 1 of a modified form of the device; and

Fig. 5 is a cross-sectional view on the line 5—5 of Fig. 4.

The device comprises a hollow form or roller 10 which in the embodiment shown in Figs. 1—3 consists of braided material 11 having inturned ends 12.

A length of pliable covered wire 13 is formed in a loop having one arm 14 extending through the roller 10 and the other arm 15 passing lengthwise over the roller. In this instance the wire 13 is bound to the inturned ends 12 of the roller by clasps 16.

17 is a ribbon or string that passes through the roller 10 and has extended end portions by which it may be tied around the head of the wearer to hold the device in place. The ribbon 17 is also fastened to the roller by means of the clasps 16. It is not necessary, of course, that the ribbon extend through the roller as separate ribbons fastened to the ends of the roller would suffice.

For use in forming a page-boy bob, the ends of the ribbon may be long enough to pass around the head twice so that the ribbon can be tied above the hair roll to hold the hair at the back of the head smooth while the roll is being set.

A modification of the invention is shown in Figs. 4 and 5 in which the form or roller 10 con-

sists of a soft rubber tube 18 preferably having perforations 19. In this instance, the two ends of the wire element 13 are fastened together, adjacent one end of the tube, by a metal clasp 20, which clasp also binds the ribbon 17.

The ends of the hair to be rolled are inserted between the roller and the wire arm 15, and the latter is pressed against the roller to grip the hair ends, after which the roller is rotated to turn the hair either under or up, as desired, and finally the ribbons are tied about the head.

Various changes in the details of construction herein illustrated and described may be made within the scope of the invention claimed.

The present invention involves an improvement 15 of the hair devices shown and described in the patents issued to me on February 7, 1939, Nos. 2,146,674 and 2,146,675.

What I claim is:

1. A hair former of the character described comprising a flexible tube, a loop of pliable wire having one arm extending lengthwise through the tube and a second arm extending lengthwise over the exterior surface thereof, and a ribbon secured within the tube having free ends extending outwardly from both ends thereof.

2. A hair former of the character described comprising a flexible tube, a loop of pliable wire having one arm extending lengthwise through the tube and a second arm extending lengthwise over the exterior surface thereof, and a ribbon secured within the tube having free ends extending outwardly from both ends thereof, the ribbon ends being of sufficient length to pass around the head and to be tied above the hair supported on the tube.

3. A hair former of the character described comprising a flexible braided tube having in-turned ends, a loop of pliable wire having an arm extending lengthwise through the tube and a second arm extending lengthwise over the exterior surface of the tube, a ribbon passing through the tube and having free end portions extending outwardly beyond the ends of the tube, and clasps for securing the ribbon and wire loop to the in-turned ends of the tube, said clasps being disposed within the ends of the tube.

4. A hair former of the character described comprising a flexible rubber tube having open ends, a loop of pliable wire having one arm extending lengthwise through the tube and a second arm extending lengthwise over the exterior surface of the tube, a ribbon passing through the tube and having free end portions extending outwardly beyond the ends of the tube, a clasp for joining the arms together to form the loop and for securing the ribbon to the loop, said clasp being disposed within the tube.

WILLIAM HUPPERT.
